CLAIM

The ornamental design for a key pad and credit card bezel for coin telephones, as shown and described.

DESCRIPTION

FIG. 1 is a left side, top and front perspective view of a key pad and credit card bezel for coin telephone showing my new design;

FIG. 2 is a right side elevational view, the side opposite being a mirror image; and

FIGS. 3 and 4 are respectively top and bottom plan views thereof;

The rear view of the front shown in FIGS. 2 and 1 is hidden from view in normal use and forms no part of the claimed design.

FIG. 1

FIG. 2

FIG. 3

FIG. 4
